[57] CLAIM

The ornamental design for a utility outlet to connect a corrugated sewer and drain pipe to a catch basin, as shown and described.

DESCRIPTION

FIG. 1 is a perspective view of a utility outlet to connect a corrugated sewer and drain pipe to a catch basin showing my new design;

FIG. 2 is a front view thereof;

FIG. 3 is a right side view thereof, the left side being identical thereto;

FIG. 4 is a rear view thereof;

FIG. 5 is a bottom view of thereof;

FIG. 6 is a top view thereof;

FIG. 7 is a cross-sectional view taken along line 7—7 of FIG. 6;

FIG. 8 is a top plan view of a second embodiment thereof, wherein the only difference resides in the double corrugated sewer pipe portion; and,

FIG. 9 is a cross-sectional view taken along line 9—9 of FIG. 8; with the broken line showing for illustrative purposes only and forming no part of the claimed design.
